7 Claims. (Cl. 250—36)

In the arrangements hitherto employed for the production of very short electrical waves, of a length for example of less than 5 metres, a high-frequency modulation of these waves is very difficult to carry out, since, as is known, any coupling element or portion of a conductor connected to the electrodes of the transmitting valve increases the wave length and also affects the generating of oscillations in other ways.

According to the present invention, for generating ultra-short waves modulated at a high frequency, an arrangement is used in which the generating of the ultra-short waves is effected by the Barkhausen and Kurz method, known in itself.

Experiments have shown that with this method of generating oscillations the influencing of the wave length by connecting the coupling and conducting elements required for high-frequency modulation can easily be prevented. For the generating of ultra-short waves modulated at a high frequency, therefore, the employment of the above-mentioned method, in combination with a modulating arrangement, such as is described below, presents special advantages.

The invention is diagrammatically illustrated by way of example in Figure 1 to 7 of the accompanying drawing, each of which represents a circuit diagram.

In Figure 1, 2 denotes a thermionic valve having a filament, a grid 4 and a braking electrode 3. To the grid 4 is applied a high positive voltage of some hundreds of volts, and to the braking electrode 3 a smaller negative voltage, which may be obtained for example from a potentiometer 6. With a particular adjustment of the operative data, ultra-high-frequency thermionic oscillations occur in the valve, the frequency f_1 of which is primarily dependent upon the working voltages applied. According to the type of valve employed, the frequency f_1 also depends upon a small oscillating circuit introduced into the valve, or upon a "Lecher" system connected to the electrodes of the valve. On the other hand the frequency f_1 of the ultra-high-frequency oscillations generated by the valve in this way is completely independent of the length and arrangements of the leads, and also of the oscillating circuits included in the leads, for instance the oscillating circuit 10, 11 in Figure 1. I assume that the thermionic valve 17 generates, with the known back-coupling connection, any desired high-frequency f_2 , which is lower than the ultra-high frequency f_1 generated by the valve 2. For the purpose of generating the high-frequency f_2 , the coil 16 is

now coupled to the oscillating circuit 12, 15 and is also coupled to the coil 11 of the oscillating circuit 10, 11. In this way there arises between the braking electrode 3 and the filament or the grid 4 a high-frequency alternating voltage of the frequency f_2 , as a result of which the ultra-high-frequency oscillations generated by the valve 2 are modulated with the frequency f_2 . The ultra-short waves modulated at a high frequency are radiated either by the system located in the interior of the valve or by a bi-pole 1 coupled thereto. The idea of the invention is not altered if instead of the high-frequency generator 12, 15, 16, 17, shown in Figure 1, any other desired high-frequency generator is employed. On the other hand it is characteristic of the invention that the exciting of oscillations in the valve 2 is effected in the braking field connection described.

The generating of the high-frequency oscillations f_2 employed for modulation may be effected according to the present invention by the same valve by which the ultra-high frequency oscillations f_1 are generated.

It has been found that thermionic valves which are connected in the braking field connection, and which oscillate at an ultra-high frequency, have a drooping current-voltage characteristic in the oscillating condition. If for example, as shown in Figure 1, between the electrode 3 and the cathode, any desired high-frequency or low-frequency oscillating circuit 10, 11 is connected, in which case the oscillator 12, 15, 16, 17 will not however be present, this oscillating circuit excites itself at its natural frequency f_2 , quite independently of the frequency f_1 of the ultra-high-frequency oscillations primarily generated by the valve 2. By this means the ultra-high-frequency oscillations f_1 are modulated at a high or low frequency according to the magnitude of the frequency f_2 . The high-frequency or low-frequency oscillations f_2 generated in this way in the oscillating circuit 10, 11 may of course be employed not only for the modulation of the ultra-short waves generated at the same time by the valve 2 but also in other ways; for instance they may serve in their turn as a transmission wave.

In Figure 2 an oscillating circuit 29, 30 corresponding to the oscillating circuit 10, 11 is connected between the electrode 3 and the grid 4 of the thermionic valve 2. The high positive voltage G is supplied to the grid by a choking coil 27. The voltage for the electrode 3 is applied at P. The frequency generated in the circuit 29—30 and modulating the Barkhausen-Kurz high frequency may be partially taken from the circuit 55

by the coil 31 for any other purposes and transmitted to another utilization circuit. Consequently, these oscillations may be used several times if desired.

5 In Figure 3 the circuit 29, 30 oscillating at the frequency f_2 is located between the grid and the cathode of the valve 2. For the rest, what has been stated for Figures 1 and 2 applies here also.

In Figure 4 the oscillating circuit consisting of 10 the coil 30 and the condenser 29 is located between an auxiliary grid and the cathode. The method of operation of this arrangement again corresponds to that of the circuits shown in Figures 1 to 3.

15 An increase in the oscillation output and in the stability of the high frequency f_2 secondarily generated by the valve 2 is obtained according to the present invention by coupling together two or more oscillating circuits located between 20 each two electrodes of the valve connected in the braking field connection.

Figure 5 shows a useful arrangement for this purpose. To the grid 4 of the valve 2 is applied a high positive voltage G , and to the electrode 25 3 a lower positive or negative voltage P . In the valve 2, ultra-high-frequency oscillations of the frequency f_1 are generated. With a suitable selection of the voltages G and P , there also arise in the oscillating circuit 10, 11, and independently thereof in the oscillating circuit 24, 25, high-frequency oscillations of the frequency f_2 . The oscillating circuits 10, 11 and 24, 25 are tuned to the same frequency and coupled to one another.

35 Figure 6 shows an arrangement by which the ultra-high-frequency oscillations of the frequency f_1 generated by the valve 2 can be modulated both with the high frequency f_2 determined by the oscillating circuit 10, 11 and at a low frequency. Part of the coil 11 forms the secondary winding or a modulating choke, upon the core 21 of which, besides the winding 11, there is a winding 22, which is connected with a low-frequency amplifier.

45 Figure 7 shows an arrangement in which the oscillating circuit 10, 11 is excited at a high frequency, and the oscillating circuit 24, 25 at a low frequency, the self-excitation of these circuits being again effected in the same manner as has 50 been described above. With this arrangement a simultaneous high-frequency and low-frequency modulation of the ultra-short waves generated by the valve 2 is likewise obtained.

Speaking generally, according to the present 55 invention, a high-frequency and low-frequency modulation of the ultra-short transmission waves is effected owing to the fact that the high-frequency by which the ultra-short waves are modulated in one of the arrangements hereinbefore described is in its turn modulated as a low frequency by known means.

What I claim is:—

1. An arrangement for generating ultra-short 60 electrical waves modulated at a high frequency, comprising a thermionic valve having a filament and consisting of a grid electrode of high positive voltage of several hundred volts and a braking electrode of a lower voltage of only a few volts in relation to the filament, producing 65 ultra-high-frequency thermionic oscillations in the valve and means for applying between two electrodes of the valve a supplementary high-frequency alternating voltage, said last mentioned means including a high-frequency, parallel- 70 lel tuned oscillating circuit, connected between 75

two electrodes of the thermionic valve, and a high frequency generator coupled to said oscillating circuit.

2. An arrangement for generating ultra-short 5 electrical waves modulated at a high frequency, comprising a thermionic valve having a filament and consisting of a grid electrode of high positive voltage of several hundred volts and a braking electrode of a lower voltage of only a few volts in relation to the filament, producing ultra-high 10 frequency thermionic oscillations in the valve and means for applying between two electrodes of the valve a supplementary high-frequency alternating voltage, the last mentioned means including an oscillating circuit connected between 15 two electrodes of the valve, the natural frequency of said circuit being essentially different from the frequency of the ultra-short waves primarily generated by the valve, whereby secondary electrical oscillations arise in this oscillating circuit. 20

3. An arrangement for generating ultra-short 25 electrical waves modulated at a high frequency, comprising a thermionic valve having a filament and consisting of a grid electrode of high positive voltage of several hundred volts and a braking electrode of a lower voltage of only a few volts in relation to the filament, producing ultra-high-frequency thermionic oscillations in the valve and means for applying between two electrodes of the valve a supplementary high-frequency 30 alternating voltage, said last mentioned means including two oscillating circuits coupled together, each being connected between two electrodes of the valve.

4. An arrangement for generating ultra-short 35 electrical waves modulated at a high frequency, comprising a thermionic valve having a filament and consisting of a grid electrode of high positive voltage of several hundred volts and a braking electrode of a lower voltage of only a few 40 volts in relation to the filament, producing ultra-high-frequency thermionic oscillations in the valve and means for applying between two electrodes of the valve a supplementary high-frequency alternating voltage, said last mentioned 45 means including a high-frequency parallel tuned oscillating circuit, connected between grid and cathode of the thermionic valve, and a high-frequency generator coupled to said oscillating circuit. 50

5. An arrangement for generating ultra-short 55 electrical waves modulated at a high frequency, comprising a thermionic valve having a filament and consisting of a grid electrode of high positive voltage of several hundred volts and a braking electrode of a lower voltage of only a few volts in relation to the filament, producing ultra-high-frequency thermionic oscillations in the valve and means for applying between two electrodes of the valve a supplementary high-frequency 60 alternating voltage, said last mentioned means including an oscillating circuit connected between braking electrode and cathode of the valve, the natural frequency of said circuit being essentially different from the frequency of the ultra-short waves primarily generated by the valve, whereby secondary electrical oscillations arise in this oscillating circuit. 65

6. An arrangement for generating ultra-short 70 electrical waves modulated at a high frequency, comprising a thermionic valve having a filament and consisting of a grid electrode of high positive voltage of several hundred volts and a braking electrode of a lower voltage of only a few volts in relation to the filament, producing ultra- 75

- high-frequency thermionic oscillations in the valve and means for applying between two electrodes of the valve a supplementary high-frequency alternating voltage, said last mentioned means including two oscillating circuits coupled together, one oscillating circuit being connected between the braking electrode and filament and the other oscillating circuit between the grid and the filament of the valve.
- 5 7. An arrangement for generating ultra-short electrical waves modulated at a high frequency, comprising a thermionic valve having a filament and consisting of a grid electrode of high positive voltage of several hundred volts and a brak-
- ing electrode of a lower voltage of only a few volts in relation to the filament, producing ultra-high-frequency thermionic oscillations in the valve and means for applying between two electrodes of the valve a supplementary high-frequency alternating voltage, said last mentioned means including a high frequency parallel tuned oscillating circuit connected between two electrodes of the thermionic valve, and a coil coupled to said oscillatory circuit, adapted to transmit the electrical oscillations of the mentioned circuit to a second utilization circuit.
